UNITED STATES PATENT OFFICE.

WILLIAM F. HUNT, OF WEST NEW BRIGHTON, NEW YORK, ASSIGNOR TO
THE C. W. HUNT COMPANY, OF NEW YORK, N. Y.

ENDLESS-CHAIN CONVEYER.

SPECIFICATION forming part of Letters Patent No. 604,234, dated May 17, 1898.

Application filed November 15, 1897. Serial No. 658,517. (No model.)

To all whom it may concern:

Be it known that I, WILLIAM F. HUNT, a citizen of the United States, residing at West New Brighton, in the county of Richmond and 5 State of New York, have invented an Improvement in Endless-Chain Conveyers, of which the following is a specification.

Endless-chain conveyers have been provided with gravity-buckets supported on 10 tracks by wheels or rollers and moved along by the connecting-chains, and the buckets have been made with lips at both the forward and backward edges, lapping one upon the other to prevent the material that is supplied 15 into the buckets falling between one bucket and the next. Buckets of this character are represented in Letters Patent No. 552,664, granted January 7, 1896, and in this patent devices are represented for swinging the 20 buckets upon their pivots in opposite directions, so as to allow the lap of the lips to be changed in order that the buckets may pass upward or downward as moved along by the chains without the lips interfering one with 25 the other. In consequence of the buckets hanging by gravity upon their cross-bars or pivots they are liable to swing, and this motion may be augmented in consequence of any 30 irregularity in the progressive movements of the chain, and when the projections or studs upon the buckets approach the stationary cams by which the buckets are caused to 35 swing in one direction or the other the buckets may be swinging in such a way that the projections will become blocked or wedged against the stationary cams, and thereby injure some of the parts.

The object of the present invention is to so place and construct the projections upon the 40 buckets that they cannot become wedged or blocked against the stationary cams as the buckets and the projections are moved along progressively and brought into contact with such stationary cams; and with this object in 45 view I place the projection that is upon the bucket above the pivot and that serves to swing the bucket in one direction to the rear of the pivot and above the same, so that when coming into contact with the stationary cam

it cannot become wedged therewith by any 50 swinging movement that the bucket may have previous to the contact with the cam of the projection upon the bucket, because such projection is pressed downward by the action of the cam as the bucket is moved along by the 55 chain and its pivotal connection. I also construct the bucket in such a manner that it can be removed from the chain with facility for 60 repairs, if necessary, and the bucket can be replaced, and in consequence of the opposite 65 ends being similarly made the bucket can be returned into position and will come correctly in relation to the stationary cams whether the bucket may have been turned end for end or not.

In the drawings, Figure 1 is an end view of 65 one of the buckets, and Fig. 2 is a cross-section of the same. Fig. 3 is a diagrammatic view on a smaller scale, showing several of the buckets and the connecting-chains and 70 illustrating the different positions assumed by the buckets as they are acted upon by the stationary cams for dumping. Fig. 4 is a similar view showing the manner of changing the 75 lap of the lips, and Fig. 5 is an elevation of one of the pivot-plates.

The buckets A are advantageously of cast metal, such as iron or steel, but I do not limit myself in this particular, and each bucket has ends 2 and 3, curved bottom 4, and inclined sides terminating with lips 5, and the chain B is composed of links with cross-bars 6 or inward-projecting lugs forming pivots for the buckets, and suitable wheels or rollers are provided for supporting the chain and 80 buckets, and the distance between one cross-bar 6 and the next is such that the lips 5 lap one upon the other sufficiently for closing any space that might otherwise exist between one bucket and the next and for preventing any 85 material dropping between the buckets as supplied into them from a suitable chute.

In order to remove either bucket from the cross-bar without disturbing such cross-bar or the chain, the ends of the buckets are 90 notched to allow the bucket to be put up against the cross-bar from below, and the pivot-plates C are adapted to fill the notches 95

above the cross-bars, and they are connected to the buckets by the bolts 7 or other rigid or separable devices, and these pivot-plates advantageously lap upon the inner surfaces of the bucket, so that the bolts may pass through the pivot-plates and into or through the buckets for holding the parts firmly together, but for allowing the pivot-plates to be easily disconnected and the buckets removed from the chain.

The inverted arch-shaped cams 8, that project from the ends of the buckets, come into contact with the stationary cam D for tipping the buckets in succession at whatever place the contents are to be discharged, as illustrated in Fig. 3, and the ribs 9, extending up from the inverted arch-shaped cams 8 to near the cross-bar pivots, strengthen the ends of the buckets, and the tipping projection 10 upon one end of the bucket is advantageously a continuation of one of the ribs 9, passing to the rear of the pivot and projecting toward the rear edge of the bucket, it being understood that the parts are so arranged and connected up in the conveyer-chain that the tipping projections 10 are all to the rear of the pivots as the buckets are carried along by the chain, and these projections 10 come into contact with the stationary cam E to tip the bucket when the lap of the lips is changed, it being understood that such projection 10 on the advancing bucket holds the bucket in a sufficiently-tipped condition to allow the next bucket to be similarly tipped without colliding, and then the projection on the front bucket passes off the cam E and allows such bucket to resume a normal position in regard to the bucket that is next in front of it and with the lap of the lips in the desired direction, the swinging and changing of the lap of the lips being similar to the operations described in the said Patent No. 552,664.

It is only necessary herein to state that in consequence of the tipping projection 10 being at the rear of the pivot and above the same the bucket may be swung upon its pivots more or less as the same is being carried along by the chain, and the projection 10 can never pass to the front of the pivot, as in the aforesaid patent, and thereby come improperly into contact with the cam and become wedged, but such tipping projection 10 will only rise and fall by any swinging movement of the bucket, and being to the rear of the pivot will underrun the inclined surface of the stationary cam, so as to be depressed thereby and swing the bucket to the proper extent and hold the same with the rear edge depressed, while the bucket next in the rear is liberated and allowed to swing, so that its advancing edge comes above the depressed lip at the rear edge of the front bucket, so as to change the lap of the lips in the desired manner, as set forth in the aforesaid patent.

65 In consequence of the arch-shaped cams 8

being similar at both sides of the center lines of the buckets they are efficient in moving in either direction, and hence the stationary cams that tip the buckets can be at either one side or the other of the track, and by 70 making both ends of the buckets similar—that is to say, the tipping projection 11 at one end of the bucket passing forward, as shown by dotted lines, and the projection 10 at the other end passing to the rear—the 75 projection 11 will come properly into position to be acted upon by the stationary cam E if the bucket is taken out and turned end for end, it being advantageous under all circumstances to place the stationary cam E in 80 such a position that it acts at the side where the tipping projections 10 or 11 are at the rear of the cross-bar pivots, and in consequence of the arch-shaped cams 8 being similarly shaped at both sides the stationary cam 85 D can be at either side of the track wherever most convenient, or two cams D may be used, one at each side of the track.

Wherever the lap of the lips may require to be changed, the buckets are swung in opposite directions sufficiently to clear each other and allow the buckets to return to their normal positions with the lips lapped in the proper direction, and in accomplishing this object a cam may be used to act upon the 95 arch-shaped cams 8 only sufficiently to swing the buckets in separating the lips instead of dumping the same, as in Fig. 3, or the buckets may be swung for this purpose by one stationary cam or bar E' acting on the advancing 100 projections 11 at one end of the buckets, (see Fig. 4,) to swing the bucket one way and the other cam or bar E to act on the rear projections 10 to swing the buckets the other way and to allow the buckets to assume their 105 normal positions with the lap of the lips changed.

I claim as my invention—

1. The combination with the chain and the pivots in an endless-chain conveyer, of buckets notched at their ends for the pivots, and removable pivot-plates at the notches and means for connecting such removable pivot-plates to the bucket ends, substantially as set forth.

2. The combination with the chains in an 115 endless-chain conveyer, of buckets and pivotal supports on the chains and a projection at the end of each bucket above the pivot and to the rear of such pivot, and a stationary cam for acting upon such projections and tipping the buckets to change the lap of the lips, 120 substantially as set forth.

3. The combination with the chains in an 125 endless-chain conveyer and the cross-bar pivots, of buckets notched at their ends to receive the pivots, removable pivot-plates and means for securing the same to the ends of the buckets over the pivot-bars, cams upon the ends of the buckets and below the pivots and stationary cams for engaging the cams 130

on the buckets in tipping the buckets for dis-
charging the contents and projections upon
the ends of the buckets above the pivots and
to the rear of such pivots at one end for en-
5 gaging a stationary cam to change the lap of
the lips, and similar projections at the other
ends of the buckets but forward of the piv-
ots, so that the buckets can be changed end

for end between the chains, substantially as
set forth.

Signed by me this 10th day of November,
1897.

WM. F. HUNT.
